INSIDE FROSTING OF NEON SIGNS

John C. Hostetter and Rowland D. Smith, Corning, N. Y., assignors to Corning Glass Works, Corning, N. Y., a corporation of New York

Application October 24, 1931, Serial No. 570,941

1 Claim. (Cl. 40—130)

This invention relates to improvements in luminescent signs of the type commonly known as "neon" signs.

In the manufacture of neon signs, it is common to employ clear glass tubing and bend it with the aid of local heating into various shapes whereupon the electrodes are introduced, the tubes exhausted and then filled with one or more gases of the noble group which includes neon, argon, helium, etc. The sign is then placed in position and current supplied to it with the result that the gas becomes luminous and forms a thread of illumination running throughout the sign letters and characters. While such signs have proven quite satisfactory, as is evidenced by their wide commercial application, they have been more or less criticized due to the fact that in some cases the light does not completely fill the tube but apparently is confined to a narrow streak of intense illumination through the center of the tube which produces glare.

An object of this invention is to improve the appearance of such signs.

Another object is to reduce the glare produced by luminescent signs.

A further object is to cause a diffusion of the light which will give the appearance of a tube filled with luminescence.

The above and other objects may be accomplished by employing our invention which embodies the inside frosting of a sign or a portion of a sign after the tubing forming it has been bent into the desired configuration.

In the drawing:

Fig. 1 illustrates an elevational view showing a sign mounted on a cradle preparatory to frosting it.

Fig. 2 illustrates a perspective view partially in section showing a finished sign.

In carrying the invention into practice, we first select a suitable piece of clear tubing and by methods well known in the art bend it into the desired shape, for instance into the letters Gas as illustrated at 10 in the drawing. The sign or an individual character thereof, as the case may be, is then supported in a cradle 11 having hollow shafts 12 which are supported in suitable bearings 13 and which are provided at their inner ends with nipples and flexible tubes 14 joining the ends of the sign 10. The flexible tubes 14 are preferably of rubber but may be composed of any flexible material such as lead or copper which is not attacked by the frosting solution. The outer end of one of the hollow shafts 12 is connected through a turnable union 15 with a pipe-

line 16 terminating in branch lines 17 and 18 which are provided with valves 19 and 20. The line 17 is adapted to be connected interchangeably with a source of water and compressed air (not shown). The line 18 extends downwardly into and near the bottom of a receptacle 21 which contains a frosting solution.

The outer end of the other hollow shaft 12 is connected through a turnable union 22 with a pipe-line 23 terminating in branch lines 24 and 25 which are provided with valves 26 and 27. The line 24 is a waste disposal line. The line 25 extends nearly to the bottom of a closed receptacle 28 from the top of which extends a suction line 29 provided with a valve 30.

By closing valves 19 and 26 and opening valves 20, 27 and 30, the frosting solution will be drawn through the sign or character so as to produce a frosted surface within the glass tubing. In order to prevent the trapping of air within the glass tubing and the consequent failure to frost its entire surface, it has been found necessary to agitate it. This may be accomplished by rotating or oscillating the cradle 11 on its horizontal axis and for this purpose a pinion 31 is secured to one of the shafts 12 in mesh with a gear 32 which may be driven in any suitable manner such as by a hand crank 33.

When sufficient frosting solution has been drawn or forced through the sign or character to completely displace the air contained therein the valve 27 is closed and the glass is allowed to frost for a time in accordance with the usual frosting practice after which the sign or character is emptied by closing the valve 20 and opening valves 19 and 27, the valve 19 being vented to the open air in this case. When the sign or character is empty of frosting solution the valve 27 is closed, valve 26 is opened and sufficient hot water is passed into the line 17 to wash out the sign or character and carry the residual frosting solution and rinse water through the line 24. After the sign or character has been completely washed out, air which may be preheated and dried if desired, is passed into the line 17 to dry out the glass tubing. Although the tubing if desired may be further treated by the fortifying step in accordance with the practice usually employed in bulb frosting, we have found this to be unnecessary as the strength of the relatively heavy-walled tubing is not too greatly diminished if this step is omitted. It will be obvious that compressed air may be used in lieu of suction to fill and empty the sign with frosting solution by substituting a closed container for the receptacle 21.

and that the direction of flow may be reversed as desired.

After the sign or character has been frosted, as indicated at 34, in the manner disclosed, the electrodes are sealed into opposite ends of the tubing as indicated at 35, whereupon the sign or character is exhausted, filled with the desired gas and sealed off, after which it is ready for use.

While in the foregoing there has been shown and described the preferred embodiment of our invention it is to be understood that minor changes in the details of construction, combina-

tion and arrangement of parts may be resorted to without departing from the spirit and scope of the invention as claimed.

We claim:

A luminous gas discharge sign comprising a glass tube bent into the desired configuration and uniformly frosted on its interior, electrodes sealed in opposite ends of the tube and gas within the tube through which electrical discharge between the electrodes takes place.
